(57) **CLAIM**

The ornamental design for a chair, as shown and described.

DESCRIPTION

FIG. 1 is a left side perspective view of the present invention with the foot portion retracted; and

FIG. 2 is a left side perspective view of present invention in a planar position with the foot portion deployed in a planar manner; and

FIG. 3 is left side perspective view of the present invention with the foot portion deployed in an angular position; and

FIG. 4 is a right side view of the present invention with the foot portion deployed in an angular position; and

FIG. 5 is a left side view of the present invention with the foot portion deployed in an angular position; and

FIG. 6 is a front view of the present invention with the foot portion deployed in an angular manner position, and the armrests also in a fold position; and

FIG. 7 is a top view of the present invention with the foot portion positioned deployed in an angular position; and,

FIG. 8 is a bottom view of the present invention with the foot portion deployed in an angular position.

The broken lines showing of parts of the drawings is included for the purpose of illustrating use and environment and forms no part of the claimed design.
